UNITED STATES PATENT OFFICE.

MAURICE ALLAND, OF ATLANTIC CITY, NEW JERSEY.

RAZOR.

Application filed June 10, 1925. Serial No. 36,103.

The object of the invention is to provide improvements in so-called safety razors and containers therefor.

Another and more specific object is to provide a safety razor holder, comprising a handle, a blade-supporting portion carried by said handle, and a retaining member pivotally secured to said supporting portion and normally engaged by a threaded extension of the handle to retain a removable blade in operative position upon said supporting portion.

A further object is to provide as a part of such a razor holder a guard composed of a transversely extending series of rotatable members, alternate members being of less diameter than intervening members, and adapted to roll over the skin and lather in advance of the blade carried by said holder, instead of scraping the lather from the skin in advance of said blade.

Still another object is to provide a blade-supporting portion, a handle rotatably secured thereto and having a threaded portion extending therethrough, and a clamping member pivotally carried by said supporting portion and adjustably engageable by said threaded portion to vary the tension with which a blade is held in operative position between said supporting portion and said clamping member.

And a still further object is to provide the supporting portion in such a razor as that last described with a convex surface, and to provide the clamping member with a concave surface of similar curvature, whereby when the threaded portion of the handle is screwed into a threaded aperture of the clamping member, the blade is flexed to varying degrees in order to most efficiently cut coarse or light-weight beards, and upon the release of the clamping member by the handle, said blade being automatically ejected from the supporting portion by the inherent resiliency of the blade, after it forces the clamping member outwardly into open position.

In addition to the foregoing, the present invention also comprises a novel box or container especially designed for the improved holder and spare blades, as well as other features hereinafter fully described in conjunction with the accompanying drawings, in which Fig. 1 is a side elevation of one embodiment of the invention; Fig. 2 is an end elevation of the same; Fig. 3 is a section on

the line 3—3 of Fig. 2, with the blade-retaining member indicated in its raised position; Fig. 4 is a top plan partially fragmentary view of the same; Fig. 5 is a plan view of the blade used with this razor; Fig. 6 is a side elevational partly sectional view of the improved container, particularly adapted for and illustrated as containing the razor illustrated in Figs. 1 to 5 inclusive; and Fig. 7 is a section on the line 7—7 of Fig. 6.

Referring to the drawings, the improved razor-holder comprises a handle 1 of any desired shape and configuration, but which, however, has a reduced end portion 2, providing a shoulder 3 in spaced relation with said shoulder, there being a washer or annular radially extending flange 4, beyond which said reduced end extension comprises an externally threaded end portion 5. A blade-supporting member comprises a body portion 6, having a centrally positioned aperture 7, through which extends the shank portion of the reduced end 2 of the handle, the washer or other form of flange 4 then lying within a recess 8 in the upper portion of said supporting member, whereby said last-named member is at all times in rotatable engagement with the handle. The upper surface of this member is furthermore provided with a plurality of lugs 9, adapted to extend normally through spaced apertures 10 in a flexible razor-blade 11, while through the centrally positioned aperture 12 in said blade normally extends the threaded end portion 5 of the handle.

This blade comprises oppositely extending parallel cutting edges 13, while its ends are concavely curved at 14, the central portions of said concaved ends being preferably curved in like manner, but upon a smaller radius, for a purpose hereinafter described. Considering the blade-supporting member transversely, the body portion 6 is provided with laterally extending reduced portions 16, each of which is provided with parallel ears 17, through and between which extends a rod 18, upon which latter are rotatably mounted alternately positioned rollers 19, and intermediate spacing rollers 20 of less diameter than said first-named rollers. Furthermore, a blade resting upon and curved in accordance with the surface of the body 6 of the holder member normally lies in spaced relation with the reduced extension 16 in order to provide oppositely positioned re-

cesses 21, in which lather and hair removed during the shaving process accumulate, without clogging the razor, as might otherwise be the case and preventing it from carrying out the function for which it is intended.

One end portion of the body 6 of the supporting member is provided with a recess 22, in which is positioned a downwardly extending lug 23 of a razor-clamping member 24, said last-named member being pivotally mounted with respect to the blade-supporting member by means of a pin or the like extending through said lug. The clamping members are furthermore provided with suitably spaced apertures 25 in alignment with and normally receiving the free end portions of the lugs 9, and with a centrally positioned, internally threaded aperture 26, which, when the clamping member is in its lowered position as shown in Figs. 1, 2 and 3, is engaged by the threaded end portion 5 of the handle to secure the blade in operative position upon the supporting member.

In the operation of this device, the clamping member is raised into the dotted line position shown in Fig. 3, and the blade placed so that the lugs 9 extend through the apertures 10 and the handle extension 5 passes through the central aperture 12. The clamping member is then lowered until the threads of the extension 5 engage the threads of the aperture 26, where, by rotating the handle 1 with respect to the blade-supporting member, the clamping member is drawn more firmly into the position illustrated, wherein the blade is flexed. This flexing may be of different degrees as desired by the user for the purpose of removing either coarse or relatively light beards, as the case may be, and the blade is held in the flexed position desired by reason of the concaved curvature of the underside of the clamping member and its oppositely tapering lateral portions 27.

For this razor there has been provided a unique box such as is shown in Figs. 6 and 7. This box primarily is rectangular in shape and comprises a bottom wall 30, side walls 31 and end walls 32. One of the end walls is provided with a hinged extension 33, which is pivotally connected to a cover comprising a top 34 and side walls 35, comprising extensions of the box walls 31 and end walls 36, and comprising extensions of the box walls 32. In order to align the lid with the body portion of the box when in normal closed position, any suitable means may be provided, such for instance as an internally positioned unitarily secured band 37, which is secured to the inner surface of the upper edge portion of the walls 31 and 32.

Within the box there is positioned a member somewhat W-shaped in side appearance,

and comprising a central inverted U-shaped portion having vertically extending parallel side sections 38, each of which is provided centrally with a cut-away portion 39, and connected at the top by oppositely positioned horizontally extending connecting portions 40, said side sections continuing adjacent to the bottom wall 30 of the box, where they are reversely bent to form upstanding supporting portions 41 for lateral oppositely extending horizontal portions 42, upon which sharp and dull blades 43, or packages containing the same, are positioned within the compartments 44. With this construction, the cut-away portion 39 permits one, after the razor has been removed from the box, to manually withdraw blades from the compartments 44 without difficulty.

Having thus described my invention, what I claim and desire to protect by Letters Patent of the United States is:

1. A razor, comprising a handle having an aperture, a pin secured in said aperture and provided upon its freely extending end with screw threads and intermediately with a radial flange, a member having an aperture through which the fixed end of said pin between the handle and the flange extends rotatably, said member being provided with spaced lugs, adapted to enter correspondingly positioned apertures in a razor blade supported by said member, a clamping member having a concavely curved lower face and a lug extending freely therefrom, pivotal means to secure said lug to one end of said first member, said clamping member being provided with apertures to receive said first lugs, and with a threaded aperture adapted to normally receive the threaded end of said pin in adjustable engagement, rotation of said handle with respect to said clamping member being operative to secure a flexible blade upon said first member with varying degrees of tension and resulting curvature of the blade, and a retrogression of the handle with respect to said clamping member operating to permit the tension of the blade upon the release of said clamping member to forcibly oscillate said clamping member outwardly and thereby release the blade from said first member, and a reversible blade normally positioned between said members and when facing in either direction having a blunt end lying in spaced relation with said lug, and being provided with oppositely directed cutting edges extending substantially the full length of said members and beyond the inner surface of the pivot lug.

2. A razor, comprising a handle having an aperture, a pin secured in said aperture and provided upon its freely extending end portion with screw threads and intermediately with a radial flange, a member having an aperture through which the fixed end of

said pin between the handle and the flange extends rotatably, said member being provided with means to position a blade thereon, a clamping member having a concavely curved lower face and a lug extending freely therefrom, pivotal means to secure said lug to one end of said first member, said clamping member being provided with a threaded aperture adapted to normally receive the threaded end of said pin in adjustable engagement, rotation of said handle with respect to said clamping member being operative to secure a flexible blade upon said first member with varying degrees of tension and resulting curvature of the blade. 10
